UNITED STATES PATENT OFFICE.

MORRIS LOWY, OF NEW YORK, N. Y.

ARMOR FOR VESSELS.

1,202,198.

Specification of Letters Patent. Patented Oct. 24, 1916.

Application filed January 6, 1916. Serial No. 70,645.

To all whom it may concern:

Be it known that I, MORRIS LOWY, a citizen of the United States, and a resident of the city of New York, in the county of New York and State of New York, have invented certain new and useful Improvements in Armors for Vessels, of which the following is a specification.

The present invention relates to an armor for war vessels, and is based upon the well known principle that a projectile will not penetrate a yielding obstruction as readily as it will a rigid and stationary one. Armors of this type usually comprise protecting plates which are mounted upon the vessels in a manner to permit of their yielding in order to arrest or absorb the force of the projectile thrown against the same. These plates are either partly or wholly submerged in water and thereby, obviously, greatly retard the normal speed of the vessel.

The main object of the present invention is to obviate this defect of the protecting devices heretofore in use, and with this object in view, it consists, broadly, in so mounting the armor or protecting plates upon the vessel that said plates can be raised or lowered, at will, to protect certain belts or portions of the vessel, or, said plates may be raised out of the water to permit the vessel to assume its normal full speed, if so desired.

With these and other objects in view, which will more fully appear as the nature of the invention is better understood, the same consists in the combination, arrangement and construction of parts hereinafter fully described, pointed out in the appended claims and illustrated in the accompanying drawings, it being understood that many changes may be made in the size and proportion of the several parts and details of construction within the scope of the appended claims without departing from the spirit or sacrificing any of the advantages of the invention.

One of the many possible embodiments of the invention is illustrated in the accompanying drawings, in which:—

50 Figure 1 is a side elevation of a vessel provided with an armor constructed in accordance with the present invention; Fig. 2 is a side elevation of a portion of said vessel

on a larger scale; Fig. 3 is a section taken on line 3—3 of Fig. 2; and Fig. 4 is a section taken on line 4—4 of Fig. 3.

Referring to the drawings, the numeral 10 indicates the hull of a war vessel or the like, to which the improved armor is designed to be applied. Upon the outer face of the hull 60 are mounted vertically extending bars 11, arranged in pairs. These bars are provided with horizontal portions 12, which are attached by rivets 13, or otherwise, to the said hull, thereby holding the said bars at a suitable distance from the outer face of the hull. With each pair of bars is associated a frame 14, carrying in a manner hereinafter to be described an armor plate 15. Inasmuch as these frames and the armor plates connected therewith are all alike, only one of the same will be described herein.

The frame 14 may be made in the form of a vertically extending plate, denoted in the drawings by the numeral 16. Upon the four corners of this plate are formed lugs 17, through which extend apertures 18. In these apertures are seated the bars 11, above-mentioned. Upon the plate are furthermore formed horizontally inwardly extending legs 19, which carry at their inner free ends anti-friction rollers 20, that are seated in the grooves 21 of channel-irons 22, the said channel-irons being disposed in parallel relation to their respective bars 11 and attached to the hull. Upon each plate are formed two pairs of legs, each pair being connected by tie-rods 23, to properly brace the same.

The armor plate associated with the frame 90 is made of two sections, to wit: 24 and 25. The section 25 extends in parallel relation to the plate 16 of the frame, and has attached thereto in any suitable manner a plurality of plungers 26, which extend in horizontal directions through apertures 27 in the plate 16. To the inner ends of the plungers is attached a vertically disposed frame 28, that is connected to the plate 16 by a plurality of heavy, normally closed springs 100 29. These springs are interposed between the plate 16 and the frame 28, their ends being attached to the said plate and frame. The springs 29 are of such dimensions that, when they are in their normally closed or compressed state, they hold the armor plate

25 a suitable distance from the outer face of the plate 16. The second section of the armor plate, that is to say the plate 24, has fixed thereto a plurality of horizontally arranged bolts 30, which extend through openings 31 in the armor plate section 25, and carry upon their inner free ends heads 31'. Between the two sections of the armor plate are interposed normally open or expanded 10 springs 32, which are fastened to the said two sections of the armor plate, and hold the same normally at a suitable distance from each other.

To the upper legs of the frame 14 is attached in any suitable manner a pair of cables 33, which run over sheaves 34 and 35, the latter being carried by brackets 36, which are attached to the hull. The cables extend into the body of the hull, and are 20 connected with suitable means for raising or lowering the frame 14 and the armor plates carried thereby. The mechanism for effecting this movement has not been shown, inasmuch as the same may be of any suitable construction and does not form part 25 of this invention.

The height and width of the armor plates may be of any suitable size, their height depending mainly upon the height of the 30 portion of the hull which they are intended to protect. Their number varies according to the requirements, their arrangement being such that they form a row of plates which embraces, as it were, the hull.

35 The operation of this device is as follows: When the armor is to be made use of against submarine attack, the frames 14 with the parts carried thereby are brought into their lowermost positions (Fig. 3). If, 40 on the other hand, that portion of the hull is to be protected against attack which is above water, the frames and the armor plates are brought into their raised positions. One of the armor plates is shown 45 partly raised in Fig. 2 of the drawings, and three of the same in their highest positions in Fig. 1 of the drawings. It is obvious that when the armor plates are in their lowermost positions, they reduce to some extent 50 the speed of the vessel. If the vessel, for some reason, is to go at its highest possible speed, all frames and armor plates are raised out of the water, in which case, obviously, they do not affect the speed of the 55 vessel.

A projectile striking the section 24 of an armor plate meets with a yielding resistance, and causes both sections of the plate to move toward the hull, thereby expanding the 60 springs 29. Before the springs 29, however, are acted upon, the springs 32 must be compressed. The shock received by the section 24 of a plate is transmitted to the plate section 25 associated therewith. The 65 shock, however, is not transmitted to the

hull, inasmuch as no springs are interposed between the armor and the hull. The yielding of an armor plate by the expansion of the heavy springs 29 prevents a penetration of the said armor plate, and the projectile 70 is brought to rest before it could reach the hull of the vessel. The frames 28 must be disposed at a distance from the outer face of the hull, which is greater than the length to which the springs 29 would be expanded 75 upon being struck by the heaviest projectile.

It is to be observed that the protecting device is mounted in such a manner upon the vessel that it can be conveniently detached therefrom. This may be desirable 80 in times of peace.

What I claim is:—

1. In an armor for vessels, the combination with the hull of a vessel, of a frame 85 slidably disposed upon the outer face thereof, an armor plate carried by said frame in parallel relation to the outer face of said hull and spaced therefrom, and springs connecting said plate and said frame.

2. In an armor for vessels, the combination with the hull of a vessel, of a vertically 90 slidable frame disposed upon the outer face thereof, an armor plate carried by said frame in parallel relation to the outer face of said hull and spaced therefrom, and 95 springs connecting said plate and said frame.

3. In an armor for vessels, the combination with the hull of a vessel, of a frame 100 slidably disposed upon the outer face thereof, an armor plate carried by said frame in parallel relation to the outer face of said hull and spaced therefrom, springs connecting said plate and said frame, and means for raising or lowering, at will, said frame 1 and the plate carried thereby.

4. In an armor for vessels, the combination with the hull of a vessel, of vertically 110 disposed guide rails upon the outer face thereof, a frame slidable upon said guide rails, an armor plate carried by said frame in parallel relation to the outer face of said hull and spaced therefrom, and springs connecting said plate and said frame.

5. In an armor for vessels, the combination with the hull of a vessel, of vertically 120 disposed guide rails upon the outer face thereof, a frame slidable upon said guide rails, an armor plate carried by said frame in parallel relation to the outer face of said hull and spaced therefrom, springs connecting said plate and said frame, and means for raising or lowering, at will, said frame and the plate carried thereby.

6. In an armor for vessels, the combination with the hull of a vessel, of a vertically 130 slidable frame upon the outer face thereof, an armor plate disposed in parallel relation to the outer face of said hull and spaced therefrom, plungers carried by said

plate and slidably supported by said frame, and normally closed springs connecting said plungers and said frame.

spaced therefrom, plungers carried by said plate and slidably supported by said frame, and normally closed springs connecting said plunger and said frame.

7. In an armor for vessels, the combination with the hull of a vessel, of vertically arranged guide rails upon the outer face thereof, a frame slidable upon said guide rails, an armor plate disposed in parallel relation to the outer face of said hull and

Signed at New York, in the county of New York, and State of New York, this 15
4th day of Jan., A. D. 1916.

MORRIS LOWY.
